Filed July 5, 1972, Ser. No. 269,251

Term of patent 14 years

Int. Cl. D13—03

U.S. Cl. D26—1 D

FIG. 1 is a front elevational view of a variable resistor showing my new design,

FIG. 2 is a top plan view thereof,

FIG. 3 is a bottom plan view thereof, and

FIG. 4 is a top right front perspective view thereof.

The undisclosed left and rear sides are substantially flat and unornamented except for the protruding stub shaft ends of the locking spring as best illustrated in FIG. 3.

I claim:

The ornamental design for a variable resistor, as shown and described.
